Patented Jan. 13, 1920.

Inventor
William W. L. Ahana,

By *C. C. Hines*,
Attorney.

UNITED STATES PATENT OFFICE.

WILLIAM W. L. AHANA, OF HONOLULU, TERRITORY OF HAWAII.

ENVELOP.

1,328,028.

Specification of Letters Patent. Patented Jan. 13, 1920.

Application filed January 3, 1919. Serial No. 289,431.

To all whom it may concern:

Be it known that I, WILLIAM W. L. AHANA, a citizen of the United States, residing at Honolulu, in the county of Oahu and Territory of Hawaii, have invented new and useful Improvements in Envelops, of which the following is a specification.

This invention relates to envelops, and particularly to openers therefor.

- 10 The object of the invention is to provide an opener comprising a severing strand extending along one of the fold lines of the envelop and connected at one end with a partially separated portion of the envelop 15 forming a tab, said tab serving as a grip whereby the thread may be grasped and manipulated to quickly and conveniently sever the envelop along the determined fold line.
- 20 A further object of the invention is to provide a novel form of tab and mode of connecting the severing strand therewith, whereby the manipulating end of the strand will be held securely against casual displacement, and whereby the same may be firmly gripped and held for the severing action.
- 25 The invention consists of the features of construction, combination and arrangement of parts hereinafter fully described and 30 claimed, reference being had to the accompanying drawing, in which:—

Figure 1 is a back view of one form of envelop embodying my invention, showing the sealing flap closed.

- 35 Fig. 2 is a similar view, showing the tab turned out so as to be gripped for the opening action.

- 40 Fig. 3 is a view similar to Figs. 1 and 2, showing the sealing flap unsealed and in open position.

In the present instance I have shown the application of the invention to an envelop of oblong rectangular form, comprising a front 1 and a back formed of a bottom flap 2, end flaps 3, and a gummed top sealing flap 4, the flaps 2 and 3 being united and forming with the front 1 the envelop body which is adapted to be sealed by folding the flap 4 over upon and securing the same 50 by its gummed margin to the flaps 2 and 3. It is, however, to be understood that the in-

vention may be applied to any other form of envelop in connection with which it may be used.

55 A severing strand 5, composed of cord or wire, is provided for severing the envelop along one of its lines of fold. This strand is glued or otherwise fastened to the envelop along the line of fold. In the present instance I have shown the strand 5 extended 60 along the line of fold between the front 1 and flap 4 for coöperation with an ungummed tab 6 formed as a part of said flap, but it is to be understood that the tab may be formed as part of any of the other flaps 65 and the strand 5 arranged along the fold line between such flap and the front 1.

The tab 6 is of suitable shape and size to enable it to be firmly gripped between the thumb and forefinger. It is formed at one 70 end of the designated flap, as the flap 4, and partially separated at its inner end therefrom by a (preferably V-shaped) notch 7. The notch 7 extends from the free edge of the flap toward its fold line, but terminates 75 short of the fold line so as to leave a narrow, intact portion 8 between such fold line and the contracted end of the notch. The tab is thus normally held to lie in the plane of the flap 4 but may be turned outward and 80 upward from the plane of the sealed flap 4, as shown in Fig. 2, into the plane of the front 1, in which operation the portion 8 is severed to entirely separate the tab 6 from the flap 4 preparatory to tearing away said 85 tab from the front 1 and separating the front 1 and tab 4 along the intervening fold line 9.

The strand 5 has an end portion 10 arranged in looped formation and cemented to 90 the underside of the tab 6, thus securing maximum strength of connection and providing a plurality of surfaces which may be gripped by the operator to enable a firm grip to be obtained. It will thus be understood that the operator may secure a firm grip upon the tab and one end of the strand and in an obvious manner may tear the same 95 free from the envelop and quickly and conveniently rip the envelop open along the 100 fold line 9. Also it will be evident that the structure is simple and may be applied to

various types of envelops without materially adding to the cost of manufacture thereof.

Having thus fully described my invention, I claim:—

- 5 An envelop comprising a body having the usual inturned flaps constituting the back of the body, one of said flaps near its extremity and the line of fold thereof being cut from its edge inwardly to a point near

the line of fold to form a tab integral with 10 and removable from the said flap, a cord within the body and extending along the line of fold of the said cut flap, and the end of said cord being glued to the underface of the said tab.

15

In testimony whereof I affix my signature.

WILLIAM W. L. AHANA.
